(57) **CLAIM**

The ornamental design for a chamfer strip, as shown and described.

DESCRIPTION

FIG. 1 is a front, right perspective view of a chamfer strip showing my new design;

FIG. 2 is a front view thereof;

FIG. 3 is a back view thereof;

FIG. 4 is a right side view thereof;

FIG. 5 is a left side view thereof;

FIG. 6 is a bottom view thereof; and,

FIG. 7 is a top view thereof.

The chamfer strip can be adapted to a top of a concrete mold. The holes allow nails and screws to fix the chamfer strip to a concrete mold therethrough.
